(57) **CLAIM**

The ornamental design for a modular shelf, as shown and described.

DESCRIPTION

FIG. 1 is a top front perspective view of a modular shelf, showing our new design.

FIG. 2 is a bottom rear perspective view of the modular shelf.

FIG. 3 is a front elevational view of the modular shelf.

FIG. 4 is a rear elevational view of the modular shelf.

FIG. 5 is a left side elevational view of the modular shelf.

FIG. 6 is a right side elevational view of the modular shelf.

FIG. 7 is a top plan view of the modular shelf; and,

FIG. 8 is a bottom plan view of the modular shelf.

The modular shelf is shown with symbolic breaks in its length, width, and height. The appearance of any portion of the article between the break lines forms no part of the claimed design. Features illustrated in broken lines form no part of the claimed design.

1 Claim, 8 Drawing Sheets
